UNITED STATES PATENT OFFICE

CHARLES L. PEIRCE, JR., OF PITTSBURGH, PENNSYLVANIA, ASSIGNOR TO HUBBARD AND COMPANY, A CORPORATION OF PENNSYLVANIA

GUY ROD

Application filed May 1, 1929. Serial No. 359,579.

This invention relates to guy rods such as are commonly employed for securing the ends of guy cables and wires used in connection with telegraph and telephone poles 5 or the like.

In using the conventional form of guy rod having a plain drop forged eye, it is customary to employ a guy thimble which is of grooved construction and curved to extend through the eye to receive and protect the guy cable or wire as it is drawn taut before being clamped. With such an arrangement it is necessary for a man to hold the thimble in proper position to keep it 15 from pinching the cable during the drawing operation. Various attempts have been made heretofore to overcome the disadvantages of this construction, but these have been unsatisfactory for different reasons, 20 such as weakening the eye, flattening the cable, expense in manufacture, or the like.

An object of this invention is to provide a device of the type set forth constructed and arranged to overcome the disadvantages 25 herein above referred to.

A further object of this invention is to provide a guy rod having an open eye construction so arranged as to produce a rod and eye having the strength of a closed, drop forged eye.

A still further object is to provide an improved arrangement of guy rod and thimble having a simple, rugged construction which will be cheap to manufacture and assemble.

These and other objects which will be apparent to those skilled in this particular art are attained by means of the invention illustrated in the accompanying drawings in which Figure 1 is a view in elevation of a 35 partially formed guy rod eye made in accordance with one embodiment of this invention. Fig. 2 is a similar view of the finished eye showing an associated guy cable thimble mounted in place. Fig. 3 is a view similar to Fig. 1 of a somewhat modified form of eye and Fig. 4 is a view showing the finished 40 form of eye of Fig. 3.

In the particular embodiments of this invention which have been chosen for the purposes of illustration, a suitable guy rod blank

5 is formed in any desired manner as, for example by drop forging, and the blank is bifurcated at one end so as to provide tines or prongs 6, each of which has an inwardly projecting stub shaft or lug 7 formed on 55 the inner face of the tines adjacent to but spaced from the ends thereof. A circular guy wire or cable receiving thimble 8 is then positioned between the prongs 6 and the latter are pressed together to the positions indicated in Figs. 2 and 4, wherein the lugs or projections abut against each other within the bore of the annulus 8 so as to form a supporting shaft 9 extending therethrough. The lugs 7 are transversely split in order 60 that the thimble 8 may be removably mounted thereon after the bifurcated end is formed. The engaging faces of the thimble and supporting shaft are so constructed and arranged that the strain to which the thimble and wire 65 are subjected by the associated guy cable is employed for the purpose of preventing separation of the bifurcations 6 and the stub shafts 7.

In the embodiment of this invention shown 70 in Figs. 1 and 2, the inner side of each of the lugs 7 slopes downward towards its extending end. The opposite faces of the lugs 7 are adapted to cooperate for forming a supporting or axle shaft for the thimble 8. The 75 thimble 8 has an inner bearing surface or bore whose outline conforms to the outline of the inner side of the lugs 7 when the latter are in their axial position. The purpose 80 thereof has been before set forth.

In the embodiment of Figs. 3 and 4 the extending lugs 7 are provided with perpendicularly projecting inner sides, and the thimble 8 has a bearing or bore surface whose outline conforms to the outline of these lugs 85 when in their axial position.

As illustrated in Figs. 1 and 2, each stub shaft is tapered from a point adjacent the supporting bifurcation where it is smallest to the outer end thereof which is substantially 90 larger. As illustrated, the upper face of each stub shaft extends perpendicularly from the associated tine, but the lower or inner face extends outwardly at an angle. As a result, the bearing face of the supporting shaft 9 95

on the bore of thimble 8 has a double taper as shown in Fig. 2 and the bore of annulus 8 is similarly shaped with its greatest diameter in the center. As a result of this construction, the strain of the associated guy cable causes such pressure between the annular bearing faces of the annulus 8 and the tapered bearing faces of the shaft 9 that the separate parts of the latter are held against separation.

In the form illustrated in Figs. 3 and 4, the engaging bearing faces of the supporting shaft 9 and the inner face of the bore in the annulus 8 are so arranged that a positive interlock is established as a result of the outward pull on the annulus 8 by the associated cable. As illustrated, the inner face of each stub shaft 7 is extended to form a projection 10 and these projections, when moved together, are received within an enlargement 11 of the annulus bore, as shown in Fig. 4, with the result that the bifurcations 6 and separate parts of the supporting shaft 9 are positively locked against separation when the annulus is moved into the locking position as a result of the strain of the associated guy cable.

What I claim as new and desire to secure by Letters Patent is:

1. A guy rod having a bifurcated end, inwardly extending thimble supporting members disposed on said bifurcations, and an annular guy wire engaging thimble mounted on said members between said bifurcations, the engaging surfaces of said thimble and said bifurcations being formed so as to prevent separation of said members.

2. A guy rod having a bifurcated end, inwardly projecting thimble supporting members formed on said bifurcations, and an annular guy wire engaging thimble mounted on said members, the bearing faces of said thimble and said members being shaped so as to employ the pull of an associated guy wire for holding said members together.

3. A guy rod having a bifurcated end provided with inwardly extending members adapted to cooperate so as to form a supporting shaft, a guy wire engaging annulus loosely mounted on said shaft and having the bore thereof formed so as to cooperate with said shaft to hold the parts thereof together when an associated guy wire is operatively associated therewith.

4. A guy rod having an eye formed by spaced prongs and inwardly extending thimble supporting members provided with enlarged inner ends and a guy wire engaging annulus mounted on said members and having a bore enlarged centrally thereof for receiving the enlarged inner ends of said members to prevent separation of said members.

5. A guy rod having a bifurcated end, inwardly extending thimble supporting members disposed on said bifurcations, the inner-

side of each of said members sloping downward toward its extending end, an annular guy wire engaging thimble mounted on said members between said bifurcations having a bore whose outline conforms to the outline of the inner side of each of the said members, so that stress upon the associated guy wire will hold said members of the bifurcated end together.

6. A guy rod having a bifurcated end, inwardly projecting thimble supporting members mounted on said bifurcations, the inner sides of each of said members having a perpendicularly extending portion at the end thereof, an annular guy wire engaging thimble mounted on said members, the bore of said thimble having an outline conforming to the outline of the inner side of each of said members so that said thimble will lock said lugs in axial position.

7. A guy rod having a bifurcated end, inwardly extending lugs disposed on said bifurcations, means for engaging a guy wire held within said bifurcated end, said lugs being transversely split so that said means can be fitted thereon after said bifurcated end is formed.

8. A guy rod having a bifurcated end, inwardly extending thimble supporting members disposed on said bifurcations, an annular guy wire engaging thimble for mounting on said members between said bifurcations, said lugs being transversely split so that said thimble can be fitted thereon after said bifurcated end is formed.

In testimony whereof, I have hereunto subscribed my name this 27th day of April, 1929.
